UNITED STATES PATENT OFFICE.

OLIVER C. RIETHMILLER AND ADELE FOWLER, OF PHILADELPHIA, PENNSYLVANIA.

DESIGN FOR A SEWING CABINET.

Application filed February 17, 1922. Serial No. 749. Term of patent 7 years.

To all whom it may concern:

Be it known that we, OLIVER C. RIETHMILLER and ADELE FOWLER, citizens of the United States, residing in Philadelphia, county of Philadelphia, and State of Pennsylvania, have invented a new, original, and ornamental Design for Sewing Cabinet, of which the following is a specification, reference being had to the accompanying drawing, forming a part thereof.

In the drawings, the figure is a perspective view of a sewing cabinet showing our new design.

We claim:

The ornamental design for a sewing cabinet as shown.

OLIVER C. RIETHMILLER.
ADELE FOWLER.
